ELECTROMAGNETIC TRANSLATING DEVICE

James Arthur Miller, Forest Hills, N. Y., assignor
to United Research Corporation, a corporation
of Delaware

Application March 21, 1931, Serial No. 524,286

13 Claims. (Cl. 179—100.41)

This invention relates to recording or reproducing sound and more particularly to an improved electromagnetic device for translating electric currents, representing sound, into phonographic records or the like, or for reproducing sound from such records.

An object of this invention is to make a phonographic record of sound in which the individual impulses are represented in accordance with their relative values in the original sound, throughout the important range of audio frequencies.

Another object is to make a record cutter which will have any desired response characteristic.

Another object of this invention is to reduce the power required to actuate an electromagnetic translating device for recording sound and to increase the sensitivity of the device for reproducing sound.

Another object is to reduce the audio frequency power formerly considered necessary for making a phonographic sound record of substantially uniform character throughout the useful audio frequency range.

Still another object of this invention is to coordinate predetermined natural vibration characteristics of the moving parts of an electromagnetic record cutter, suitably damped, with the characteristics of an attenuation network, to obtain a desired response characteristic for the combined cutter and network.

A further object of this invention is to make a sound recorder, the record-making element of which will have substantially constant integrated velocity for the important audio frequencies when energized by equal voltages at said frequencies.

Recording and reproducing devices heretofore used have not been entirely satisfactory because their non-linear characteristics result in distortion of the sound to be recorded or reproduced. This distortion is due to resonant vibration of the armatures of said devices, at least to a great extent. Attempts have been made to so design moving elements or armatures that their resonant frequencies will be outside of the important range of audio frequencies. Such attempts have not been successful because the important range of audio frequencies for high quality recording and reproduction of sound is very wide. This range is considered to include all frequencies from approximately 100 cycles to approximately 5000 cycles, and wider ranges are considered important if the recording or reproduction is to be of very high quality. It has been found that curves representing the response-frequency char-

acteristics of ordinary electromagnetic translating devices have at least one prominent peak, and sometimes more. The construction of these devices has been such that an attempt to reduce one peak results in the displacement or increase of a peak in some other part of the curve, due, apparently, to the rigid construction of their moving elements. Attempts have been made to damp the excessive vibration of an armature at its resonant frequency by pressing blocks of rubber or other soft material against the armature or by immersing the entire moving structure in oil. It has been found, however, to obtain a flat response curve by damping alone, that the sensitivity of the device is reduced to such an extent that an excessive amount of power is required to drive it when used as a recorder, or additional amplification is required when the device is used as a reproducer or pick-up.

According to the present invention and in order to accomplish the objects above mentioned, a translating device is provided in which the moving element is not rigid but has a plurality of degrees of freedom of vibration, in the audio range, which may be independently controlled. It has been discovered that if parts of an armature are proportioned to have desired resonant frequencies individually, and if proper coupling is provided between the armature parts, that the transfer of energy between them may be controlled. It has also been discovered that a desirable way to effect this energy transfer is to establish a harmonic relation between the resonant frequencies of various parts of the armature. A moving element constructed in accordance with this invention will have a plurality of degrees of freedom of vibration, the frequencies of which are determined by the mass, resilience and physical dimensions of its parts. A curve showing the response-frequency characteristic of an electromagnetic device having a moving element in accordance with this invention will show, if corrective means are not employed, a plurality of peaks corresponding to the natural periods of vibration of the armature as a whole and its parts. There may be other peaks arising from the interaction of one part of the moving element upon another part through the coupling between them. The higher peaks and especially those occurring in the lower frequency range may be reduced by proper damping, but the amount of damping required is much less than is needed to obtain a fairly flat curve by damping alone. Damping is preferably accomplished by immersing the moving element in a liquid. The amount

of damping may be readily controlled by associating adjustable surfaces with surfaces of the moving element. The remaining and usually broad peaks may then be reduced by placing an 5 attenuation network in series with the actuating coil of the device.

A very desirable response-frequency curve for a sound recorder or reproducer is a substantially straight horizontal line over a large part of the 10 important audio frequency range, which tapers off at the low frequency end. Such a characteristic may be obtained, with high sensitivity, by taking advantage of and properly selecting the resonant frequencies of the moving element as 15 explained above. A sound recorder or reproducer constructed in accordance with this invention will have such a characteristic curve if the moving element is designed to have a plurality of resonant frequencies at selected points in the 20 audio frequency range, sufficient damping is provided to reduce the amplitude of the resonant vibrations without, however, unduly affecting the sensitivity of the device, and the remaining peaks are compensated by the selective transmission of the attenuation network.

Other objects and structural details of this invention will be apparent from the following description when read in connection with the accompanying drawings, wherein:

30 Fig. 1 is a diagrammatic view of a reed and is intended to illustrate a principle involved in this invention;

35 Fig. 2 is a perspective view of a complete translating device made in accordance with this invention;

Fig. 3 is a perspective view of the moving element of the device shown in Fig. 2;

Fig. 4 is a cross section, on the line 4—4, of the moving element of Fig. 3;

40 Fig. 5 shows the cover of the device shown in Fig. 2;

Fig. 6 is a cross section of the device shown in Fig. 2 with some parts removed for clearness and shows, diagrammatically, a circuit connected to 45 the actuating coil of the device;

Fig. 7 is a side elevation, on a larger scale, of the adjustable damping means of the device shown in Figs. 2 and 6;

Fig. 8 illustrates adjusting and holding means 50 for the pole pieces of the device shown in Fig. 6;

Fig. 9 shows curves of response versus frequency which have been obtained from the device illustrated in Fig. 2.

If a reed, indicated generally by reference character 1, Fig. 1, has a plurality of sections *a*, *b* and *c* having different cross sections, each of the sections *a*, *b* and *c* may have a different natural period of vibration with a node at the point of juncture with the next section for *b* and *c* or at 55 the support 2 for section *a*. By varying the physical dimensions of the sections *a*, *b* and *c*, their natural periods of vibration may be changed independently of the other sections. The resonant vibrations of the reed will depend, however, 60 not only on the natural period of vibration of each section, but the reed will have resonant vibrations due to the vibrations of two or more sections taken together and due to combinations of sectional vibrations as influenced by the coupling between the sections. Such a reed will, therefore, have a plurality of resonant frequencies of vibration. It has been discovered that if the natural vibration periods of two or more sections are harmonically related, the transfer of 65 energy between them is a harmonic transfer 70

and that if energy is expended at the fundamental frequency, it is not present at the harmonic frequencies, or, stated in another way, if the energy is properly controlled at the low frequency, the amplitude of vibration may be controlled thereby at the harmonic frequencies. 5

These discoveries have been put to a useful purpose in the design of the moving element for a translating device or cutter such as shown in Fig. 2. It should be understood that an electromagnetic translating device which will cut a record may also be used as a reproducer. The moving element or armature of the device shown in Fig. 2 is illustrated in detail in Fig. 3. The armature proper is indicated by reference numeral 10 and has a support, preferably in the form of a torsional spring 11, provided with holes 12, through which screws may be passed to support the moving structure in the frame of the electromagnetic device. It will be noted that the armature 10 is relatively thick at the point of juncture with spring 11 and at its end portions 13 and 16. To the end portion 13, a relatively thin vane 14 is attached but the vane may be integral with the armature 10, as shown in the cross sectional view (Fig. 4). To the opposite end 16 of the armature is attached in any suitable manner a needle or a stylus support 17 to which a stylus 18 may be secured. The portion 10 with ends 13 and 16 of the moving element is the only portion 30 which must be made of magnetic material, preferably steel containing about 4% silicon. The other parts of the moving element are preferably non-magnetic, such as hard brass or bronze for spring 11 and aluminum for stylus support 17 35 and vane 14. The stylus 18 is usually cut from a sapphire and has an accurately ground point so that it will cut a groove with smooth walls of the desired shape.

In Fig. 2, the stylus support 17 and the stylus 40 18 are shown protruding from the bottom of the cutter. Adjacent the stylus is a pin or ball 19 in a suitable holder 21 preferably in the form of a bent lever hinged on a rod 22. In the sound-recording operation, the smoothly rounded pin 45 19 rests upon the wax, or other blank on which the sound is to be recorded, in advance of the cutting stylus 18 and determines the depth of cut. The position of the pin 19 relative to the stylus 18 is adjustable by a screw 23 acting on the opposite end of the lever 21 which is held against the screw 23 by spring means (not shown). Rod 22 and lever 21 are detachable so that pin 19 may be easily refinished or replaced. A thermometer 24 50 may be mounted on the outside of the case 25 with its bulb in close contact therewith to indicate the temperature of the device when in use. Extending portion 26 provides means for securing the cutter to a suitable supporting arm (not shown). 60

In Fig. 6, the moving element is shown in section and in relation to other parts of the cutter. A magnet 28, preferably a small but strong permanent magnet, provides flux in the air gaps adjacent the portions 13 and 16 of armature 10. 65 These air gaps are formed by magnetic pole pieces 30 and 31 having surfaces in close contact with the ends of magnet 28, and having other surfaces disposed adjacent the thick part 16 of the armature. The air gap adjacent end 16 of the armature is adjustable by sliding the pole pieces 30 and 31 toward or away from the armature and securing them in position on the plate 32 (Fig. 8). The air gap adjacent end 13 of the armature may be adjusted by slidably positioning plates 33 and 75 70

- 34 on pole pieces 30 and 31, respectively, and securing them in position by means of screws 35 and 36, or other suitable means. Disposed over the vane 14 is a member 38 having a slot therein.
- 5 Member 38 is movable toward and away from the armature preferably by screw member 39 (Fig. 7) which passes through the cover 40 of the cutter and has a head or knob 41 on the outside of the cover. Member 38 is provided with suitable guiding means, such as angle plates 43 and 44, and a pin 45 slidably mounted in angle plate 46. By varying the adjustment of member 38 by means of screw 39, varying portions of the vane 14 may be disposed within the slot in the member 38.
- 10 Angle pieces 43, 44 and 46 are secured to a support 47 which, in turn, is secured to the cover 40.
- An actuating coil 50 of a suitable number of turns and size wire is disposed between the pole pieces 30 and 31 and surrounds the armature 10.
- 20 Leads 51 and 52 serve to connect coil 50 to a suitable source of audio frequency power, or to a circuit carrying the current which represents the sound to be recorded. An attenuation network, indicated generally at 53, and which may comprise resistance 54, condenser 55, and inductance 56, all connected in parallel, may be inserted in lead 52.

After the parts are assembled in the case 25 (Fig. 2), it is filled with oil, or other damping medium, through an opening 55 in the cover 40 (Fig. 5). The cover 40 is provided with terminals 57 through which connections may be made to the coil 50. The oil in case 25 is prevented from running out by a suitable gasket 58 surrounding the stylus support 17. Gasket 58 may be made of rubber or other elastic or flexible material which will permit movement of the stylus. The gasket is suitably secured to the casing 25, as by clamping ring 59.

40 Some of the principal dimensions of a moving element which has been found to give satisfactory results, are as follows:

Width of armature 10 and ends 13 and 16	.160
45 Thickness of ends 13 and 16	.075
Thickness of upper portion of armature 10	.045
Thickness of lower portion of armature 10	.042
Length of upper thin portion of armature 10	.155
Length of lower thin portion of armature 10	.198
50 Diameter of stylus support 17	.052
Vane 14	.435 x .300 x .0045

(All the above dimensions are in inches)

55 Representative response characteristics of a cutter made in accordance with this invention and as illustrated in the drawings are shown in Fig. 9. The curve indicated by I is a response characteristic of the cutter with no oil in the case 25 and with the actuating coil 50 connected directly to a constant voltage, variable frequency source. It will be noted that this curve shows four distinct resonant peaks; the first occurs at approximately 900 cycles; the second at the fourth harmonic of 900, or 3600 cycles; the third at the eighth harmonic of 900, or 7200 cycles; and the fourth at the tenth harmonic, or 9000 cycles.

70 The 900 cycle peak is due to the mass of the armature 10, 18, 16, stylus bar 17, stylus 18 and vane 14, supported by the stiffness of spring 11, which constitutes a resilient fulcrum. This resonant period may be increased by stiffening spring 11 and by decreasing the mass of the armature or the parts attached thereto. It may 75 be decreased by decreasing the stiffness of spring

11, or increasing the mass of the armature and attached parts.

The 3600 cycle resonant peak is due to the vane 14 moving with reference to armature end portion 13. Its period may be controlled by 5 changing its mass and stiffness, a long thin vane having a lower period than a short thick vane.

The 7200 cycle peak is likewise due to the proportions of the longer end of the armature 10, extending between its center and end portion 16.

The 9000 cycle peak is due to the shorter end of the armature bar extending from its center to end portion 13.

15 The proportions as above given provide for an armature system which has a natural resonant peak of 900 cycles due to the bodily movement of the entire armature, stylus, and damping vane, whereof said vane has a natural resonant peak which is the fourth harmonic thereof, with the 20 longer end of the armature having a resonant peak which is the eighth harmonic thereof, and a shorter end of the armature having a peak which is the tenth harmonic thereof.

25 In general, the proportions of the stiffness and mass of the different parts of the armature may be computed from the following: The square root of the quotient of the mass divided by the stiffness of an armature portion, stylus or vane, should be a multiple of the square root of the 30 quotient of the mass of the armature system as a whole, divided by the stiffness of the spring support 11.

Curve I clearly shows the plurality of resonant peaks obtained with an undamped armature. 35 Curve II is a characteristic of the same cutter under the same conditions but with the case filled with castor oil. It will be noted that the resonant peaks have been smoothed out or merged, but a characteristic of this type is not 40 entirely satisfactory because of the relatively high response in the middle range of frequencies. Curve III was obtained with the same cutter and oil but with an attenuation network, as shown in Fig. 6, connected in series between the 45 actuating coil and the energy source. This attenuation network comprised a resistance of 1000 ohms, a capacity of .03 microfarad, and an inductance of 250 millihenries. The series resistance 54 tends to reduce the response equally 50 throughout the entire audio frequency range but is more effective at the very low frequencies. The inductance 56 in parallel with resistance 54 increases the relative response at the low frequencies because of the relatively low impedance 55 of the inductance at these frequencies. The response at the upper end of the scale is increased due to the relatively low impedance of the condenser 55 at the high frequencies. The small, broad peak at the upper end of curve 60 III is probably due to the effect of series resonance between condenser 55 and actuating coil 50. If no attenuation network were used and sufficient damping were applied to the moving element to obtain a curve as flat as curve III, 65 the relative response would have been considerably less than that obtained by the combination of moderate oil damping and the attenuation network, as shown in curve III.

70 The initial response of the device is made very high due to the plurality of resonances, as shown by curve I, so that sufficient damping can be applied to merge the resonant peaks, but with the sensitivity of the device maintained at a high level. The net result is a cutter which has high 75

sensitivity with a practically flat characteristic curve. The gradual falling off of the characteristic curve at the low frequency end is desirable to prevent excessive swings of the recording stylus at the low frequencies, which would result in cross-overs in the record grooves. This falling off is compensated in the reproducing operation because pick-up devices ordinarily used are more sensitive at the low frequencies.

10. Characteristic curves in which a desired band or bands of frequencies are relatively high or low may be obtained from translating devices made in accordance with this invention by arranging the resonance peaks of the various parts 15 of the moving elements to fall either within or without the desired bands depending upon whether the said bands are to be increased or reduced, respectively. Sufficient damping may then be provided to reduce the resonant vibrations to the desired level and compensating networks may be connected in circuit with the actuating coil to reduce any undesired frequency bands.

The usual method of using the device shown 25 in Fig. 2, is as follows: The device is connected to the output of a suitable amplifier, the input of which is connected to a microphone. The cutter is supported by a suitable arm which grips the extending portion 26 and which is arranged 30 to guide the cutter over a wax record blank. The sapphire pin 19 rides on the smooth surface of the moving wax 60, and the stylus 18, which is slightly lower than the pin 19, cuts a groove in the wax. The variations of current in coil 35 50 produce corresponding vibrations of the stylus 18 which, in turn, makes an undulating groove in the wax. If the cutter is then connected to the input of a suitable amplifier and sound reproducer and its supporting arm allowed to move 40 freely, the stylus will follow the groove in the wax and the sound recorded thereon will be reproduced.

The degree of damping of the oil depends on its temperature. After the temperature characteristic of the cutter is determined, uniform damping may be obtained by adjusting the screw 39 in accordance with the temperature of the oil, as indicated by thermometer 24.

While there is here described but a single embodiment of the device of this invention, it is adapted to still other modifications therefrom without departure from the inventive concept disclosed, and it is therefore desired that only such limitations shall be imposed upon the appended 55 claims as are stated therein or required by the prior art.

I claim:

1. A translating device comprising a pair of magnetic poles providing two air gaps therebetween, an armature having a portion thereof disposed in each of said gaps, and means for resiliently supporting said armature between said poles; said armature having portions thereof extending beyond said gaps, the armature and its 60 extending portions having several sections thereof differently proportioned with respect to mass, dimensions and resilience, whereby said armature has a plurality of harmonically related natural periods of vibration.
70. 2. A translating device having an armature, portions of which have different masses and cross sections of such value that the natural frequency of vibration of one portion of said armature is harmonically related to the natural frequency of vibration of another portion thereof.

3. The combination of an armature wherein the relation of mass to stiffness is different for different portions thereof, said portions having their natural frequencies of vibration in harmonic relation in the audio frequency range, 5 means for partially damping the vibration of said portions, and means for producing a field of force for said armature.

4. An electromagnetic translating device comprising a pair of adjacent magnetic poles forming two air gaps therebetween, an armature disposed in said gaps, a support for said armature comprising a torsion spring, the lengths of those portions of said armature between the point of support and said pole pieces being unequal and each of said armature portions being relatively thicker opposite the said poles than between the poles and the point of support, a relatively thin vane protruding from one end of said armature, and a stylus support protruding from the opposite end of said armature.

5. A translating device as defined in claim 4 in which said armature portions and said vane are formed from one piece of magnetic material.

6. A translating device as defined in claim 4 in which the natural vibration periods of said vane and said stylus support are harmonically related and the natural period of vibration of at least one of said portions of the armature is harmonically related to the said natural periods of the 30 stylus support and vane.

7. An armature for an electromagnetic device comprising a body portion, a relatively thin vane protruding from one end of said body portion, a stylus support protruding from the opposite end 35 of said body portion, and a stylus secured to said support, the natural vibration periods of said vane and said stylus support with its stylus being harmonically related.

8. An acoustic device comprising an electromagnetic having an armature, a spring support for said armature, a portion of said armature being vibratile with respect to the armature as a whole, the stiffness of said spring support also the stiffness of said vibratile portion and the masses of 45 said armature as a whole and of said portion thereof being so related that the natural period of vibration of said armature as a whole is harmonically related to the natural period of vibration of said portion thereof, whereby the harmonic vibrations are overemphasized.

9. An acoustic device according to claim 8, wherein said spring support is arranged at one side of the center of said armature whereby the ends of said armature beyond said spring support are of unequal length.

10. An acoustic device according to claim 8 wherein said spring support is arranged at one side of the center of said armature whereby the ends of said armature beyond said spring support 60 are of unequal length, and wherein the short end of said armature is provided with a damping vane and the longer end of said armature is provided with a stylus.

11. An electromagnetic translating device comprising an armature having a plurality of vibratile sections having different mass-stiffness ratios respectively with harmonically related natural periods of vibration in the audio frequency range, means for partially damping the vibrations of said 70 sections, and means for producing a magnetic field for said armature.

12. A record cutter comprising an armature having a plurality of vibratile sections of different cross sectional areas respectively wherein the 75

relation of mass to stiffness of said sections is such that the natural periods of vibration thereof are over-emphasized at harmonic intervals, a magnetic field for said armature, and mechanical and electrical damping for said armature whereby the response thereof falls off at frequencies in the neighborhood of 100 cycles and whereby the response is peaked above a frequency in the neighborhood of 5,000 cycles.

13. A translating device having an armature, portions of which have different masses and cross sections of such values that the natural frequency of vibration of one portion of said armature is harmonically related to the natural frequency of vibration of a plurality of other portions thereof.

JAMES ARTHUR MILLER.
